JOHN H. GRAYSON, OF ATHENS, OHIO, ASSIGNOR TO THE J. H. GRAYSON MANUFACTURING COMPANY, OF ATHENS, OHIO, A CORPORATION OF OHIO.

BURNER FOR GAS FIRES.

1,424,760.

Specification of Letters Patent. Patented Aug. 8, 1922.

Application filed May 3, 1921. Serial No. 466,409.

To all whom it may concern:

Be it known that I, JOHN H. GRAYSON, a citizen of the United States, residing at Athens, in the county of Athens and State of Ohio, have invented certain new and useful Improvements in Burners for Gas Fires, of which the following is a specification.

This invention relates to gas burners in general and more particularly to burners for 10 gas fires.

Gas fires, especially those having radiant mantles are now commonly used throughout the country, both in connection with artificial gas and with natural gas.

15 In many localities both natural gas and artificial gas are available. In some instances part of a community, has natural gas while another part has artificial gas. In other cases the same main, may at one 20 time furnish artificial gas and at other times natural gas may be fed into it to help carry the peak load or vice versa.

It is a common experience that burners adapted for the use of natural gas do not 25 satisfactorily burn artificial gas and vice versa. This is due to the fact that natural gas is much richer than artificial gas. The relative quantities of gas and air to be brought together in order to obtain perfect 30 combustion are very different in the two cases. With natural gas only about one half the volume of gas is consumed for producing a certain number of B. T. U. as compared with the usual artificial gas or, conversely, it takes about double the volume of 35 artificial gas as compared with natural gas to produce the same thermal effect, while the quantity of air entering into combination is correspondingly smaller in connection with artificial gas than with natural 40 gas.

It is often necessary to rebuild the burner of a gas fire adapted for one kind of gas to adapt it for use with another kind of gas.

45 What has been said in respect to the differences between natural gas and artificial gas applies also, although to a lesser extent, to the differences between different kinds of artificial gas and natural gas respectively.

50 It is the principal object of this invention to provide a gas burner adapted to produce perfect combustion whether applied to

natural gas, artificial gas or to different kinds of either gas.

It is a more special object to provide a 55 burner with means for controlling the relative quantities of gas and air to bring about perfect combustion under all practical conditions.

My invention, briefly stated, is a universal 60 gas burner i. e. a burner comprising means for controlling the relative quantities of gas and air essential for producing perfect combustion under all practical conditions.

For a full understanding of the invention 65 reference is made to the accompanying drawings in which

Fig. 1 is a plan view of the burner;
Fig. 2 is a plan view, partly in section;
Fig. 3 is a side elevation thereof;
Fig. 4 is a longitudinal section thereof;
Fig. 5 is a perspective view of a detail 70 forming an important part of the invention;

Figs. 6 and 7 are sectional views thereof 75 in different operative positions;

Fig. 8 is an end view of the burner and showing fragmentary parts of a gas fire;

Figs. 9 and 10 are fragmentary sectional 80 views of a detail; and

Fig. 11 is an end view of the detail arrangement shown in Figs. 9 and 10.

As best shown in Figs. 3 and 4 the burner consists of an upper manifold passage 10 and a lower mixing tube 11, which arrangement has been found advantageous in connection with a plurality of burner units, particularly for gas fires. However, this arrangement forms no part of the invention.

The burner shown comprises seven burner 90 units although a greater or smaller number can be used, the number of burner units not being material to the invention.

The manifold tube 10 consists of a lower part 10^a cast in one piece with the mixing 95 tube 11, and an upper part 10^b, both parts having machined surfaces and apertured lugs 12^a and 12^b respectively for receiving screws or bolts. The upper part has seats for the burner grids 13 which may be of 100 any suitable construction. Above the burner grids and spaced therefrom is support 14 for the radiant mantles 15 indicated in part in Fig. 4 together with the fire back 16.

Between the upper part 10^b and the lower part 10^a is fitted a plate 17 containing a damper or register. The plate 17 is stamped out to provide a series of apertures 18 and 5 upon the upper surface of the plate 17 is mounted a slide 19 having apertures 18^a corresponding to the apertures 18 of plate 17. The slide 19 is held in sliding contact with the plate 17 by means of tongues 20 struck 10 up from plate 17 or otherwise formed and bent over the slide 19. The plate 17 has apertures 21 spaced to register with certain of the lugs 12^a and 12^b so that its position relative to the manifold is fixed.

15 At one end the slide 17 has an upturned perforated ear 22 adapted to form a bearing for a swivel 23 at the end of a screw 24. The screw 24 extends through a threaded bore in the end of the upper part 10^b of the 20 manifold and by turning it one way or the other, the slide 17 may be moved correspondingly. At one end of the slide 17 is a top 25, which may conveniently be an extension of the upturned portion 22, and at the opposite 25 end is a stop 26 for limiting the movement of the slide in both directions. The stops abut against the adjacent tongues 20 and the arrangement is such that the extent of movement is no greater than the width of an 30 aperture 18. The relation is furthermore such that when the stop 26 abuts against the adjacent tongue 20, the apertures 18 and 18^a are in register and that when the stop 25 abuts against its adjacent tongue 20, the 35 apertures 18 are covered by the webs between the individual apertures 18^a of the slide 17, these webs having the same width as the apertures.

Thus the effective passage areas leading to 40 the grids 13 may be varied from a maximum equalling the sum of all the apertures to a minimum which is approaching zero. Theoretically zero value can not be reached because there is no such absolutely tight fit 45 between plate 17 and slide 19 as would completely stop the passage of gas and no such tight fit is in fact intended.

The gas admitting mechanism is attached to the open end of the mixing tube as clearly 50 shown in Figs. 1, 2 and 3. This mechanism has apertured lugs 27 and 28 by which it may be attached to the end face of the mixing tube 11 which has bracket arms 29 to receive the screws passing through the lugs 55 27 and 28 respectively.

The gas admitting mechanism comprises the usual admission valve mechanism including a stem 30 and a hand grip 31 for turning it and a regulating orifice for controlling 60 the flow of gas.

The regulating orifice comprises a slotted tapered sleeve 32 having a sliding fit in a bore 33 of a nozzle element 34 which has a small aperture 35 in alignment with the bore of the 65 sleeve 32. The wings 36 of the sleeve bear

at their free ends against the tapered front wall of the nozzle element 34 so that by movement of the sleeve against this tapered wall the wings are contracted and the effective aperture of the sleeve is reduced. 70 When the pressure is released, the spring wings react against the tapered wall and push the sleeve back again thus again increasing the effective orifice.

I preferably use an eccentric 37 carried 75 upon a pintle 38 for actuating the sleeve 32. While there is considerable latitude in regard to the arrangement, I preferably provide the pintle with a groove 39 engaging a pin 40 for holding the pintle 38 80 against axial movement. As best shown in Fig. 10 the pintle 38 extends into the gas passage so that the eccentric 37 bears against the end of the sleeve 32. The relationship of the parts is, of course, such that in the 85 position of the eccentric in Figs. 9 and 10 the sleeve 32 is forced inwardly into the nozzle element 34 to its limiting position and that when the eccentric has been turned 180 degrees from the position shown, the 90 sleeve will spring back to the other extreme position, maintaining contact with the eccentric during the movement.

While the arrangement just described is broadly not new, the particular construction, which I believe to be new, has the advantage that no jamming of the sleeve is possible. When the eccentric 37 is turned beyond the point corresponding to the extreme inward position of the sleeve 32 it 100 will automatically recede again and release the sleeve. The pintle 38 will remain in any position since the reacting force of the wings 36 is not sufficient to turn it.

The valve stem 30 carries a pin 41 adapted to abut against stop shoulders 42 and 43 to limit the angular movement of the valve stem as is usual in similar arrangements.

The bracket arms 29 project rearwardly from the mixing tube to space the gas admitting mechanism therefrom, thus providing sufficient space for the entrainment of air into the mixing tube, as is likewise common. An air sleeve 44 may be provided having sliding movement in the mixing 115 tube 11 toward and away from the nozzle element 34.

The support 14, as best shown in Fig. 3, has downwardly extending legs 45 which have threaded bores adapted to receive the 120 screws extending through some of the lugs 12^a. The support 14 may thus be rigidly attached to the manifold in spaced relation above the grids 13. The mantles 15 have integral ears 46 fitting into corresponding 125 recesses 47 in the support. In front of the mantles the support 14 is formed with raised portions 51 which together with the ears 46 hold the mantles in fixed position. The recesses 47 are preferably formed by 130

providing a plurality of spaced ribs 48. The fire back is preferably provided on its base with a recess 53 fitting over the raised portion 54 and with a projection in such recess fitting into the depression 49 in the surface of the support 14 (Fig. 1). The support may also be provided with upstanding portions 50 bearing against the rear surface of the fire back, as indicated in Fig. 8.

The burner carries at its ends blocks 52 which fit against the side walls of the usual gas fire casing (not shown) and have tapped holes by which they may be secured to such casing.

The swivel screw 24 and the valve mechanism project laterally from the casing enclosing the burner and thus are readily accessible for operation.

20 The operation is as follows:

When the gas fire is applied to natural gas the sleeve 32 is closed to substantially its closing position thereby reducing the effective orifice to a minimum. The velocity 25 of the gas is thereby correspondingly high while the volume admitted per unit of time is relatively small. Due to the increased velocity the amount of air drawn in by the negative pressure is necessarily a maximum. 30 These are exactly the conditions required for a perfect combustion. According to the particular qualities of the natural gas, the orifice may be slightly adjusted, but it must always be very small. Within the range of 35 adjustment involved, the velocity of the gas and the corresponding negative pressure vary also slightly to bring about the proper condition of combustion for the particular quality of the natural gas. Thus a slightly 40 leaner natural gas will be given a slightly smaller velocity and will consequently draw in a slightly smaller amount of air while the volume admitted per unit of time is slightly larger than when a relatively richer 45 gas is used and vice versa.

When the gas fire is used with artificial gas, the sleeve is retracted to approximately open position so that the velocity of the gas and the negative pressure are correspondingly reduced causing only a relatively small amount of air to be entrained. On the other hand the volume admitted is relatively large.

These, again, are exactly the conditions 55 required for a perfect combustion. The artificial gas is lean as compared with natural gas and does not need as much air for perfect combustion as the natural gas, particularly since it usually contains air. The 60 ratio of gas and air is thus automatically changed to suit the particular conditions. A slight range of adjustment may of course be necessary to take care of the particular qualities of the artificial gas used, but the 65 orifice is substantially open.

All of these adjustments, however, would be for naught if not simultaneously some other provisions were made to regulate combustion. This leads us to the most material part of the invention.

Assume that a gas fire of the usual kind adapted for perfect combustion with natural gas were connected to artificial gas. If the valve were entirely opened, the flame would be blown up with a hissing noise indicating 75 that too much air is drawn in. When the valve is more or less closed, the flame would strike back to the nozzle. Thus regulation of the valve alone would be inadequate.

Conversely if a gas fire of the usual kind 80 originally adapted for perfect combustion with artificial gas were connected to natural gas with the valve wide open, the gas would evolve dense smoke indicating incomplete combustion. Closing the valve would 85 gradually reduce the smoke but would not eliminate it. The flame and therewith the heat, would decrease and the flame would finally strike back.

The reason is probably this:

The difference in the qualities of natural 90 gas and artificial gas is such that within the range of control in the usual burner construction as at present available, the amount of air drawn in by the natural gas would 95 not be sufficient to afford complete combustion if the burner is adapted for artificial gas and the amount of air drawn in by artificial gas would be too great if the burner is originally constructed for natural 100 gas. Adjustment of the usual air sleeve at the end of the mixing tube would be of no avail.

Applicant has recognized the conditions 105 essential for obtaining perfect combustion with one and the same burner construction and has introduced a draft regulator between the nozzle element 34 and the flame.

With natural gas the register 17, 19 is drawn wide open to make the effective passage substantially a maximum, the draft is thus also a maximum. The gas issuing from the nozzle of the admission mechanism therefore encounters only a small resistance and the high velocity of the stream can be 110 really made effective to draw in the large amount of air necessary to bring about complete combustion, while this high nozzle velocity would not have the desired effect were the stream to meet a relatively greater 115 resistance.

When artificial gas is used, the damper or register is substantially closed. The draft is thus reduced to a minimum. The effective passage is large enough to let the gas 125 pass but the draft is reduced to such an extent that no more than the necessary amount of air is drawn in at the nozzle 34. It should be noted that the gas being lighter than air has a natural tendency to rise 130

through the mixing and manifold tubes and does not need any special force behind it. The clearance space between the slide 19 and the plate 17 is sufficient to let all the 5 gas pass. The gas issues from the nozzle in a large slow stream passing slowly through the mixing tube and draws in only a small amount of air.

In both cases, however, the register may 10 be slightly adjusted from the two extreme positions according to the qualities of the particular gas used alone or concurrently with the sleeve 32 as above pointed out.

At any rate by the concurrent adjustment 15 of the orifice of sleeve 32 and the register it is possible to condition the burner for perfect combustion with natural gas and artificial gas whatever their properties may be.

20 In practice the admission orifice is adjusted for the particular gas to be used and once set, the adjustment need not be disturbed. If the B. T. U. of the gas per unit volume are known, the adjustment may be 25 made in the factory. The other adjustments are thereafter made only by means of the register.

While the particular forms of gas admission mechanism and damper mechanism 30 show what applicant considers as preferred embodiments of the invention, there is of course a considerable range of mechanisms for carrying out the invention.

It may be said in addition that the form 35 of grid may be also varied within wide limits, provided however that the resistance to the flow of gas must be small so as not to introduce a resistance which would make the damper mechanism inoperative for the 40 purpose specified.

As indicated in Figs. 1 and 2 the grids have four relatively large apertures, although other forms may be chosen. I prefer to have those apertures disposed to one 45 side of the center so that the flame is principally directed against the back of the radiant mantles.

Although I have the invention shown as applied to radiant gas fires, it is needless 50 to say that it is of more general application and may be applied in different burner construction.

I claim:—

1. In a burner construction for natural 55 gas and for artificial gas, a grid, a mixing tube, a conduit between the grid and the mixing tube, having a cross sectional area at least as large as the effective aperture of the grid and means for constricting the said cross-sectional area.

2. In a burner construction for natural 60 gas and for artificial gas, a grid, a mixing tube, a conduit between the grid and the mixing tube, having a cross sectional area at least as large as the effective aperture

of the grid and an adjustable register occupying said cross-sectional area.

3. In a burner construction for natural 70 gas and for artificial gas, a plurality of grids, a mixing tube, a manifold between the grids and the mixing tube, having a cross-sectional area at least as large as the sum of the effective apertures of the grids and an adjustable register occupying said cross-sectional area. 75

4. In a burner construction for natural 80 gas and for artificial gas, the combination of a grid, a mixing tube, a conduit between the grid and the mixing tube, having a cross-sectional area at least as large as the effective aperture of the grid, means for constricting said aperture and a gas admission mechanism having a variable orifice.

5. In a burner construction for natural 85 gas and for artificial gas, a plurality of grids, a mixing tube, a manifold between the grids and the mixing tube, having a cross-sectional area at least as large as the sum of the effective apertures of the grids, means for constricting the said cross-sectional area and a gas admission mechanism 90 having a variable orifice.

6. A gas burner having a passage between the gas inlet and the top of the burner of considerably greater cross-sectional area 95 than the effective aperture at the top and means in said passage for varying the resistance to the flow of the gas.

7. A gas burner having a passage between the gas inlet and the top of the burner of a 100 cross-sectional area larger than the effective aperture at the top, means extending across said passage defining a plurality of apertures and means for variably constricting said apertures. 105

8. A burner for gas fires having a plurality of burner grids, a manifold tube, a gas inlet, a plate extending across the manifold and defining a plurality of apertures and means for variably constricting the said 110 apertures.

9. A burner for gas fires having a plurality of burner grids, a manifold tube, a gas inlet and an adjustable register extending across the manifold. 115

10. A burner for gas fires having a plurality of burner grids, a manifold, a gas inlet, means for varying the orifice of the inlet and means extending across the manifold for varying the resistance to the gas flow. 120

11. In a gas burner, a manifold consisting of an upper section carrying burner grids and a lower section having a gas inlet, a plate defining a plurality of apertures, means for variably constricting the said apertures, said plate being disposed between the upper and the lower sections of the manifold, means for securing the said sections and the said plate together and 125 130

means for actuating the constricting means.

12. In a gas burner, the combination with the burner top and a mixing tube, of a gas admission mechanism having a variable orifice and means between the mixing tube and the burner top for varying the resistance to the gas flow.

13. In a gas burner, the combination of a manifold comprising an upper section carrying burner grids, a lower section, a mixing tube integral with the lower section, a register between the said sections, a support for mantles and a fire brick above the upper section and means for securing the 10 said sections, the register and the said support together to form a unitary structure.

14. In a burner construction, a grid, a mixing tube, a conduit between the grid and the mixing tube and means in said conduit 20 for varying the effective cross-sectional area thereof, the grid, the mixing tube and the said conduit having such characteristics that when the effective cross-sectional area

of the conduit is nearly a maximum, the burner construction is adapted for burning natural gas and when the effective cross-sectional area of the conduit is nearly a minimum, the burner construction is adapted for burning artificial gas.

15. In a burner construction, a grid, a mixing tube, a conduit between the grid and the mixing tube and means in said conduit for varying the effective cross-sectional area thereof, the grid, the mixing tube and the said conduit having such characteristics that when the effective cross-sectional area of the conduit is nearly a maximum, the burner construction is adapted for burning natural gas and when the effective cross-sectional area of the conduit is nearly a minimum, 40 the burner construction is adapted for burning artificial gas, and gas admission mechanism having a variable orifice.

In testimony whereof, I affix my signature.

JOHN H. GRAYSON.
